US00D558150S

(12) **United States Design Patent** (10) Patent No.: **US D558,150 S**
(45) Date of Patent: **** Dec. 25, 2007**

(54) **SAFE FUSE TERMINAL**

(75) Inventor: **Ming-Lin Yang**, Hsinchu (TW)

(73) Assignee: **Photo-Top Technologies Co., Ltd.**,
Hsin-Chu (TW)

(**) Term: **14 Years**

(21) Appl. No.: **29/262,026**

(22) Filed: **Jun. 26, 2006**

(51) LOC (8) Cl. **13-03**

(52) U.S. Cl. **D13/161; D13/178**

(58) Field of Classification Search D13/158-184;
439/687; 337/163, 198, 206, 230, 264, 265

See application file for complete search history.
